WINDING MACHINE

David J. Kelman, Brooklyn, N. Y.

Application November 18, 1931, Serial No. 575,705

6 Claims. (Cl. 242—6)

This invention relates to winding machines. It is particularly directed to a machine for winding a decorative cord or the like elongated strip or strand about an annular member, for example, in 5 making a Christmas wreath.

An object of this invention is to provide in a machine of the character described having an annular rotatable winding member and means for supporting an annular core to be wound in a plane 10 perpendicular to the winding member and with said core passing through said winding member, highly improved means for permitting removal of the core from the winding member and for rotating the core simultaneously with rotation of 15 said winding member.

A further object of this invention is to provide in a machine of the character described improved means for regulating the relative speeds of rotation of the winding member and core.

20 A still further object of this invention is to provide a neat, compact and rugged machine of the character described, comprising comparatively few and simple parts, easy to assemble and operate, which shall be relatively inexpensive to 25 manufacture, smooth and positive in operation and yet practical and efficient to a high degree in use.

Other objects of this invention will in part be obvious and in part hereinafter pointed out.

30 The invention accordingly consists in the features of construction, combinations of elements, and arrangement of parts which will be exemplified in the construction hereinafter described, and of which the scope of application will be 35 indicated in the following claims.

In the accompanying drawings, in which is shown one of the various illustrative embodiments of this invention,

Fig. 1 is a front elevational view of a machine 40 embodying the invention with a core mounted thereon for the winding operation;

Fig. 2 is a cross-sectional view taken on line 2—2 of Fig. 1;

Fig. 3 is a fragmentary top plan view of a portion of the core supporting means;

Fig. 4 is a sectional developed view taken on line 4—4 of Fig. 2; and

Fig. 5 is a cross-sectional view taken on line 5—5 of Fig. 2.

50 Referring now in detail to the drawings, 10 designates a machine embodying the invention, here shown for the purpose of illustration only, in the form of a device for winding a decorative cord or other elongated strand or strip about an 55 annular core for making a Christmas wreath, it

being understood however, that the machine may be used for winding a great variety of annular or ring members. The machine 10 comprises a base 11 on which is mounted an upstanding segmental housing 12 rotatably supporting an annular ring shaped gear 13, rotated in the manner hereinafter described. The machine 10 further comprises means for supporting and rotating an annular core 14 in a plane perpendicular to the plane of the ring gear 13 and with said core passing 60 through said gear, the supporting and rotating means being in the form of a member 15 operatively connected to the gear 13, for simultaneous rotation therewith, and a pair of spaced idlers or rollers 16 and 17 engaging the core at points 65 spaced preferably 120° from the member 15. The winding of the core 14 is accomplished by means of thread, cord or the like winding strip 20 unwinding from a spool 21 rotatably mounted on a spindle 23 fixed to the annular gear 13.

70 The housing 12 preferably comprises a vertical upstanding plate member 25 having a foot portion 27 attached to the base 11 by means of bolts 27a or the like fastening devices. The plate member 25 is formed with a curved segmental portion 80 26, preferably of more than 180°. The segmental portion 26 terminates in radial outwardly extending ear portions 28 and 29, disposed at the front of the machine. The portion 26 of the housing member 25 is further formed preferably 85 midway between the ear portions 28 and 29 with a radial outwardly extending ear 30. Integrally formed with said plate member 25 and extending at right angles thereto from the outer rim thereof is a curved wall 31 following the outer contour 90 of the member 25. The wall thus extends around the ears 28, 29 and 30 and along the curved portion of the segment 26 and along the side edges of the member 25 down to the foot 27 thereof. The wall portion 31 is formed with a plurality of 95 spaced enlargements or bosses 32 for the purpose hereinafter stated. Attached to the free edge 33 of the wall portion 31 is a flat plate member 34 substantially similar in shape to the wall portion 25 and parallel thereto and likewise having a 100 foot 35 attached to the base 11 by means of bolts 36 or the like fastening devices. The attachment between the member 34 and the member 25 may be made by means of bolts 37 extending through suitable aligned openings in the bosses 32 and 105 outer edge of the member 34. It will be noted that the housing 12 formed by members 25 and 34 is channel shape in cross-section for rotatably receiving the annular ring shaped gear 13. After the gear is assembled with the housing, the former 110

cannot be removed because the housing is more than 180° as shown in Fig. 2. The construction of the gear 13 will now be described. Said gear 13 comprises a main section 40 having an annular angle preferably greater than the angle of the housing 12, so that the ends 41 and 42 of the section 40 may project beyond the ear portions 28 and 29, as illustrated in Fig. 2 of the drawings. The section 40 comprises a body 43 and plates 44 and 45 attached to sides of the body 43 by means of screws 46 or the like fastening means. The body 43 is formed with gear teeth 47 on the outer periphery thereof and the plates 44 and 45 preferably project beyond said teeth to guard the operator's hands against contact with said gear teeth.

Pivoted to the end 42 of section 40 is a complementary segmental section 48 completing the gear 13. The section 48 likewise comprises a body 49 and plates 50 and 51 attached to the sides thereof by means of screws or the like fastening means. Fixed to one end 52 of section 48 is a pin 53 pivotally received within a socket 54 formed in the adjacent end 42 of section 40. The opposite end of the body 49 is formed with a beveled surface 56 and with a notch or depression 57. The end 41 of the section 40 is formed with a recess 60 housing a ball 61 pressed by a spring 62 into engagement with the notch 57. The plate 44 of section 40 preferably extends beyond the end 42 of said section, as shown at 64, and one end of the plate 50 terminates short of the end 55 of the body, as shown at 65, to permit said end 55 of the body to contact the projecting portion 64 of said plate 44.

It will now be understood that the section 48 may be pivoted about the pin 53 to provide an opening for inserting the core 14 within the ring-shaped gear or for removing the core therefrom. Upon applying side pressure to the upper end of the section 48 to the right, as shown in Fig. 4, said section will pivot about the pin 53 to the position shown in dot-dash lines in Fig. 4. The section 48 may be moved back to normal position by merely pushing the same against the projecting portion 64 of the plate 44, the spring pressed ball 61 snapping into the socket 57 for retaining said section 48 in normal position.

For rotating the gear and supporting the same within the housing 12 there is provided a pair of idler gears 70 and 71 suitably mounted for rotation within the ear shaped portions 28 and 29 of the housing 12 and meshing with the teeth of the gear 13. The ear shaped portion 72 of the plate 34, parallel to the ear 30 of the plate 25, is formed with a bearing opening 73, and said ear portion 30 is formed with an aligned bearing opening 74. Extending through said openings and journaled therein is a shaft 75 extending to one side of the housing 12, as shown in Fig. 1 of the drawings. Fixed to the portion of the shaft 75 extending between the ears 30 and 72, is a gear 76 likewise meshing with the teeth 47 of the gear 13. The shaft 75 is preferably supported on a stanchion 77 mounted on base 11 and formed with a bearing 78 for receiving said shaft. For rotating said shaft 75, there is fixed thereto a pulley 79 driven by a belt operated in any suitable manner, for example, an electric motor, not shown. It will now be understood that rotation of pulley 79 will cause rotation of gear 13 thru shaft 75 and gear 76.

For rotating the core actuating member 15, simultaneously with gear 13, there is provided a shaft 80 parallel to the shaft 75 and journaled in

a bearing 81 formed in said stanchion 77. One end of said shaft 80 may be further supported and journaled within a bearing 82 formed in the plate portion 34 of the housing 12. The shafts 75 and 80 preferably extend beyond the stanchion 77, as at 83 and 84, and fixedly mounted on said extensions are complementary conical pulleys 85 and 86, receiving a belt 87. It will thus be seen that the shaft 80 is driven through the belt 87 received in complementary grooves of the pulleys 85 and 86. Said pulleys 85 and 86 are preferably oppositely tapered so that the relative speeds of rotation of the shafts 75 and 80 may be changed by merely shifting the belt 87 from one set of grooves to another set of grooves.

Mounted on the base 11 is an upstanding housing 90 formed with bearings 91 on opposite side walls 91^a thereof receiving said shaft 80 which extends through said housing. Fixed to the portion of the shaft 80 extending within the side housing walls 91^a is a worm 92 for the purpose hereinafter appearing. Rotatably mounted on said housing 90 is a shaft 93 disposed at right angles to the shaft 80 and journaled within bearings 94 formed on the front and rear walls 94^a of said housing. Fixed to the portion of the shaft 93 extending between said front and rear walls 94^a of the housing is a worm wheel 95 meshing with said worm 92. The shaft 93 preferably projects forwardly of the housing 90 and fixedly mounted on the front end of said shaft 93 is said member 15 adapted to engage the core 14. It will now be understood that said member 15 will be rotated simultaneously with gear 13, thru shafts 93, 80, pulleys 85, 86 and shaft 75.

Said member 15 may be made of soft rubber or any other suitable material and preferably comprises the rear wall or disc 97 and a frusto-conical portion 98 tapering inwardly toward the disc 97. Obviously the member 15 may have any suitable shape for effectively frictionally engaging the core 14 for rotating the same by a friction drive. In the present instance the core 14 is formed with a flat, rear surface 99 and a semi-cylindrical front surface 100. Thus the disc 97 is adapted to engage the surface 99 of the core, and the conical surface of the portion 98 of said member 15 is adapted to engage the surface 100 of the core.

Means is provided for adjustably supporting the idler roller 16 in contact with the core 14. To this end a bracket 102 is attached to the base 11, for example, by means of screws 103. Extending through the lower end of the bracket 102 is a bolt 104. Said bolt 104 serves to attach to the bracket 102 an arm 105 in the form of an elongated strip 130 having a slot 106 therein receiving said bolt therethrough. A spacing sleeve 107 may serve to separate the bracket portion 102 from the arm 105. It will thus be seen that the longitudinal as well as the angular position of the arm 105 may be adjusted by manipulating the nut 103 of the bolt 104. Fixed to the outer end 110 of the arm 105 is a pin 111 on which is rotatably mounted the member 16. Said member 16 is preferably substantially similar in shape to the member 15 and is likewise provided with a rear disc portion and a frusto-conical portion for engaging the core 14. It will now be understood that the portion of the member 16 may be adjusted as required, depending upon the size of the core to be wound, and then fixed in adjusted position.

The third core supporting idler or roller 17 is preferably supported for movement into or out of contact with the core, in the manner herein-

after appearing, to permit positioning of the core for the winding operation and removal of the core after the same is fully wound. To this end there is fixed to one end of the base 11 a pair of parallel rods 115 and 116 and slidably mounted on said rods is a block 117 having suitable openings slidably receiving said rods therethrough. Screwed to an extension of said block 117 is a stud or pin 118 parallel to the axis of the core, and rotatably mounted on said pin is an arm 119 formed with a longitudinal slot 120. Extending through said slot 120 is a pin 121 fixed to said arm in adjusted position by means of a nut 122. The member 17 is rotatably mounted on said pin 121 and is likewise formed with a rear disc portion and a frusto-conical portion for engaging the core 14. It will be noted that the member 17 may be adjusted along the length of arm 119 due to the slot 120, and then fixed in a suitable adjusted position. Furthermore, the arm 119 may be swung about the pin 118 into or out of contact with the core 14. Thus after the winding operation, the arm 19 may be swung counterclockwise, looking at Fig. 1, to move the member 17 away from the core to permit removal of the core.

As stated above, a spool of thread to be wound about the core 14 may be rotatably mounted on pin 23 fixed to and extending to one side of the gear 13. Fixed to said gear 13 is a block 124 extending tangentially of said gear and formed with a slot 123 receiving the thread 20 from said spool 21, said thread passing from said slot to the core, as illustrated in Fig. 1. To prevent too rapid unwinding or racing of the spool 21 there is fixed to the gear 13 a pin 125 on which is rotatably mounted a leaf 126 pressed by means of spring 127 mounted on said pin, against said spool.

The operation of the device will now be readily understood. With the operating motor for the machine not running, and arms 119 swung to the left, the upper end of the section 48 of the gear 13 is first pressed sideways for causing pivotal movement of said section. The upper end 55 of section 48 is thus separated from the adjacent end 42 of section 40. The core 14 may now be passed through the opening between said separated ends of the sections 48 and 40 and moved into contact with the members 14 and 16. The arm 119 may then be swung for moving the member into contact with the core 14. The section 48 is then swung back and snapped into place to complete the gear 13. The operating motor is then started and the pulley 79 rotated for simultaneously rotating the gear 13 and the member 15. The spool is thus rotated with the gear around the core and the core rotated about its axis. One end of the thread 20 is of course, tied or otherwise attached to the core 14, before the motor is started. As the gear 13 rotates, the spool 21 will rotate therewith for winding the thread 20 about the core 14 and since said core also rotates, the thread will completely cover the core. Obviously, the relative speed of rotation depends upon the width of the thread or strip 20. When the core is completely covered by the winding element 20, the motor is stopped and said strip or element severed and tucked underneath the covering or tied to the core. The arm 119 is then swung outwardly or counterclockwise, looking at Fig. 1, and the section 48 is again swung out of alignment with the section 40 to permit removal of the core.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative, and not in a limiting sense.

Having thus described my invention, I claim as new and desire to secure by Letters Patent:—

1. In combination, a base, a segmental housing mounted thereon, a ring shaped gear rotatably mounted within said housing, a rotatable shaft mounted on said base, a gear mounted on said shaft and meshing with said first named gear, a second shaft parallel to said first shaft mounted on said base, a pair of oppositely disposed conical pulleys mounted on said shafts, respectively, a belt interconnecting said pulleys, and means for supporting an annular core for rotation in a plane perpendicular to the plane of said gear, said core having a flat surface and a curved surface, said means comprising a member geared to said second shaft having mounted thereon a member formed with a flat disc portion, engaging the flat surface of said core and a frusto-conical portion, the small end of which contacts the disc, engaging the curved surface of said core.

2. In combination, a base, a segmental housing mounted thereon, a ring-shaped gear rotatably mounted within said housing, a rotatable shaft mounted on said base, a gear mounted on said shaft and meshing with said first named gear, a second shaft parallel to said first shaft mounted on said base, a pair of oppositely disposed conical pulleys mounted on said shafts, respectively, a belt interconnecting said pulleys, and means for supporting an annular core for rotation in a plane perpendicular to the plane of said gear, said core having a flat surface and a curved surface, said means comprising a member geared to said second shaft having mounted thereon a member formed with a flat disc portion, engaging the flat surface of said core, and a frusto-conical portion, the small end of which contacts the disc engaging the curved surface of said core, a bracket attached to said base, and a member rotatably mounted on said bracket having a disc portion in the plane of said first disc portion and likewise engaging the flat surface of said core, and a frusto-conical portion having the small end thereof in contact with said disc portion, and engaging the curved surface of said core.

3. A wreath winding machine comprising, in combination, an annular ring-shaped gear, means for supporting the same for rotation, means for supporting an annular core for rotation in a plane perpendicular to the plane of said gear, said core having a flat surface and a curved surface, a member having a flat wall portion in a plane perpendicular to said gear arranged to engage said flat surface of the annular core and a frusto-conical portion arranged to engage said curved surface of the annular core and having the small end thereof contacting said flat wall, and means for simultaneously rotating said gear and member.

4. A wreath winding machine comprising, in combination, an annular ring-shaped gear, means for supporting the same for rotation, means for supporting an annular core for rotation in a plane perpendicular to the plane of said gear, said core having a flat surface and a curved surface, a member having a flat wall portion in a plane perpendicular to said gear arranged to engage said flat surface of the annular core, and a frusto-conical portion arranged to engage said curved surface of the annular core.

curved surface of the annular core and having the small end thereof contacting said flat wall, and means for simultaneously rotating said gear and member, and means for changing the relative speed of rotation of said member and gear.

5. A core winding machine comprising a base, a gear housing mounted on said base comprising a channel member terminating in peripherally-spaced ends, said channel member having a plurality of outwardly projecting portions, a ring gear having gear teeth on the outer periphery thereof mounted for rotation in said housing, said ring gear having a section pivoted at one end thereof about an axis disposed in a plane perpendicular to the axis of said gear and also at right angles to a radius of said gear, and movable through the space between said ends of the housing to permit the positioning of a closed annular core within said gear, means for supporting said

20

ring gear in said channel member comprising an idler gear mounted in one of said outwardly projecting portions of the channel member in mesh with said ring gear, and means for driving said ring gear comprising a gear mounted in another of said outwardly projecting portions of the channel and in mesh with said ring gear.

6. A core winding machine comprising a gear housing of channel shaped cross-section and terminating in peripherally spaced ends, a ring gear mounted for rotation in said housing, said gear having a section pivoted at one end thereof about an axis perpendicular to the axis of said gear and also perpendicular to a radius of said gear and movable through the space between the ends of the housing to permit the positioning of a closed annular core within said gear.
